UNITED STATES PATENT OFFICE

93,952

DESIGN FOR AN AUTOMOBILE

Thomas O. Theobald, Detroit, Mich.

Application January 7, 1933, Serial No. 46,750

Term of patent 3½ years

To all whom it may concern:

Be it known that I, THOMAS O. THEOBALD, a citizen of the United States, residing at Detroit, in the county of Wayne and State of Michigan, have invented a new, original, and ornamental Design for an Automobile, of which the following is a specification, reference being had to the drawing wherein the figure is a perspective view of an automobile embodying my design.

As illustrated in drawing, the dominant feature of the design resides in the trumpet-like horns associated with the vehicle body.

I claim:

The ornamental design for an automobile substantially as shown and described.

THOMAS O. THEOBALD.
